Primary Examiner — Mark A Goodwin*(74) Attorney, Agent, or Firm* — Norton Rose Fulbright Canada(57) **CLAIM**

We claim the design for a steering wheel adapter for agricultural vehicle vision guidance system, as shown and described.

DESCRIPTION

FIG. 1 is a perspective view of a steering wheel adapter for an agricultural vehicle in accordance with the present design.

FIG. 2 is a front view thereof.

FIG. 3 is a rear view thereof.

FIG. 4 is a first side view thereof, the opposite second side view being a mirror image thereof.

FIG. 5 is a top view thereof; and,

FIG. 6 is a bottom view thereof.

The broken line portions are included to show environmental and/or unclaimed subject matter only and form no part of the claimed design.

1 Claim, 3 Drawing Sheets(56)
